UNITED STATES PATENT OFFICE.

GEORGE H. FOX, OF BOSTON, MASSACHUSETTS, ASSIGNOR TO THE AMERICAN ARMS COMPANY, OF SAME PLACE.

LOCK FOR FIRE-ARMS.

SPECIFICATION forming part of Letters Patent No. 255,274, dated March 21, 1882.

Application filed March 5, 1881. (No model.)

To all whom it may concern:

Be it known that I, GEORGE H. FOX, a citizen of the United States, residing at Boston, in the county of Suffolk and State of Massachusetts, have invented certain new and useful Improvements in Breech-Loading Fire-Arms; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in gun-locks for breech-loading fire-arms; and it consists in the peculiar construction and combination of parts hereinafter set forth and claimed.

The drawings represent, in Figure 1, a vertical longitudinal section of a gun-stock containing my improvements. Fig. 2 is a plan with the top snap-lever thrown to one side, showing the position of the hammer within the stock or lock-chamber. Fig. 3 is a side view of the hammer, and Fig. 4 a cross-section through the intermediate locking-shaft.

A in the drawings represents part of the stock of a top snap-action breech-loading fire-arm. B is the hammer, C, the hammer-lever, by means of which the hammer is actuated, either cocked or uncocked. This lever, as shown in the drawings, lies closely to the side of the stock, and is so situated that the hand is in the usual position for firing when cocking the piece, and the pressure of the thumb on the lever on either side, provided one has double barrels, is sufficient to cock the piece without removing the forefinger from the trigger. The hammer B is securely fastened on a movable pin or shaft, j, passing through the lock-plates, which pin has on its extreme end the lever C. On the rear side of this hammer is formed a curved hook, g, which catches upon a pin or stud, f, formed on the side of the middle part of a stirrup, d. The upper end of said stirrup engages with the operating end of the mainspring H, and the lower end of said stirrup is curved to form an upwardly-turned

hook, d', which catches against a fixed stop-pin, f'.

G designates the trigger. h designates the spring which forces the same into engagement with tumbler, and a designates the trigger-guard. The rebound of the hammer to half-cock, after driving the firing-pin into the cartridge, is caused partly by the weight of lever C acting on shaft j, and partly by the nose of trigger G as it is forced against the suitably inclined forward part of the bottom of the hammer-tumbler. To allow this rebound it is of course necessary that the operation of the main-spring should be checked before the hammer completes its forward movement. This has hitherto usually been done by arranging a stop 55 above the mainspring, so that the latter will strike against it. I however effect the same result by arranging my stop f' above the lower end of the stirrup d and shaping said lower end of the stirrup into a hook, which will engage 60 therewith. The shock and the wear are thus transferred from the mainspring to the stirrup.

In ordinary top snap-action breech-loading fire-arms it is usual to have the arrangement shown in the drawings Fig. 1—viz., the lever 75 c, the intermediate shaft, E, with eccentric stud i for actuating the catch F, and the spring e for keeping the bolt in its locking position except when moved by the hand-lever c—or a combination very nearly the same. Now, one great 80 objection heretofore is in the shape of the shaft E, which is usually made with two arms to allow of the passage of the firing-pin in a rectilinear path of movement, and at the same time of the rotary motion of the shaft E while locking or unlocking the barrels. While this form of bolt accomplished this purpose, still it was expensive in manufacture and occupied much space. In my present improvement, as shown, the shaft E is made straight and full in its entire length, thereby retaining its strength, or the same strength with less metal, as it has no elbows or offsets. Through it I drill a hole at right angles to the axis of its movement. This is for the firing-pin, and then in order to obtain free and unobstructed passage of the pin through the shaft at the same time that I procure rotary motion of the shaft I cut away the 85 90 95

latter in the manner shown in Fig. 4, making the slots *b b* on either side of the firing-pin sufficient to allow for the extreme movement of the shaft *E* and lever *c*. The shaft portion of the above arrangement is made much simpler by the latter improvement, and fully as efficient.

Having thus described my invention, what I claim, and desire to secure by Letters Patent, is—

1. The combination of stirrup *d*, having hook *d'* on its lower end, with stop-pin *f'*, arranged to be engaged by said hook, mainspring *H*, operating to lift said stirrup, and hammer *B*, pro-

vided with a hook, which catches against a ¹⁵ stud on said stirrup, substantially as set forth.

2. In combination with a firing-pin operating in axial alignment with the bore of the barrel or barrels, a vertical top-snap locking-shaft, said shaft being constructed with a passage ²⁰ for said firing-pin to play through.

In testimony whereof I affix my signature in presence of two witnesses.

GEO. H. FOX.
